GAME BOARD

Berry F. Laws, Jr., Kansas City, Kans.

Application February 15, 1954, Serial No. 29,027

Term of patent 3½ years

(Cl. D34—5)

The figure shown in the drawing is a perspective view of the game board.

The back of the game board is plain, without ornamentation.

I claim:

The ornamental design for a game board, as shown and described.
